BEAM HANGER

Roy A. Delay, Seminole, Okla.

Application October 1, 1941, Serial No. 413,223

1 Claim. (Cl. 74—103)

This invention relates to a beam hanger for a reciprocal well pump operated by a walking beam, and has for the primary object the provision of a connection between the walking beam and the polish rod of the pump especially adapted to relieve the polish rod of lateral strain due to the conventional movement of the walking beam and which tends to crystallize the polish rod or place undue wear thereon and thereby insure the life of a polish rod for an indefinite period of time.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a side elevation, partly in section, illustrating a beam hanger connected to a polish rod of a pump and to a walking beam, a fragmentary portion of which is shown.

Figure 2 is a sectional view taken on the line 2—2 of Figure 1.

Figure 3 is a sectional view taken on the line 3—3 of Figure 1.

Figure 4 is a perspective view illustrating a pivot member.

Figure 5 is a perspective view illustrating a self-adjusting arm.

Figure 6 is a sectional view taken on the line 6—6 of Figure 2.

Referring in detail to the drawings, the numeral 5 indicates in entirety a beam hanger forming the subject matter of the present invention and especially adaptable for connecting a polish rod 6 of a reciprocal pump to one end of a walking beam 7. The support of the walking beam is indicated by the character 8 and the pivotal connection between the walking beam and the support 8 is indicated by the character 9. Due to the pump end of the walking beam moving in the arc of a circle when actuating or reciprocating the polish rod 6 of the pump, a lateral strain is placed upon the polish rod causing the latter to drag against its stuffing box 10 which within a short period of time brings about crystallization of the polish rod by placing undue wear thereon.

Through the use of the beam hanger 5 constituting the present invention, this lateral strain on the polish rod is eliminated thereby increasing the life of the polish rod.

10 The beam hanger 5 includes a substantially L shaped bracket 11, pivots 12 and 13 and connecting rods 14 joining said pivots 12 and 13. The beam hanger 5 further includes a self-adjusting means 15 coacting with the walking beam and the bracket 11 in maintaining the reciprocation of the polish rod in a vertical plane during the normal movement of the walking beam 7.

Usually the pump end of the walking beam 7 is bifurcated, as shown at 16, and the arm portion A of the L-shaped bracket 11 extends therethrough. Said arm portion A carries a pivot pin 17 received in bearings 18 mounted on the bifurcated end of the walking beam. The arm portion A of the L-shaped bracket 11 is in the form of a flat plate 19 provided with bolt openings to receive bolts 20.

20 A bearing plate 21 is secured on the plate 19 of the L-shaped bracket 11 by the bolts 20 which also secure onto the bearing plate 21 retaining straps 22.

The bearing plate 21 is provided with a groove 23 forming a seat for a pivot member 24 retained in the groove 23 by the straps 22. The bearing member 24 at its ends is provided upon its top face with bearing portions 25 each having a sharp contact or bearing edge 26 to be engaged by bearings 27 to which the connecting rods 14 are threaded, as shown at 28. To removably secure the bearings 27 on the bearing portions 25 removable collars 29 are secured on the bearing member 24 by set screws 30. The collars cooperate with opposite edges of the L-shaped bracket 11 in preventing the bearings 27 from moving endwise of the pivot or bearing member 24.

35 The pivot 13 may be constructed similarly to the pivot 12. The pivot 12 being of the construction described heretofore in detail may operate with a minimum amount of friction.

The self-adjusting means 15 includes an arm 40 31 provided with a bifurcated end 32 apertured, as shown at 33, to receive a pivot 34 provided on the arm portion A of the L shaped bracket 11 a limited distance below the pivot 17. The arm 31 partly lies in the bifurcation 16 of the walking beam and its free end is provided with a screw threaded opening 34 to receive a set screw 35 which bears against the bracket 11.

45 As the pump end of the walking beam moves upwardly in the arc of a circle and which movement tends to cause a lateral movement of the connections between said walking beam and the pump, the arm 31 contacts the wall C of the bifurcation 16 causing the beam hanger 5 to adjust itself to maintain the entire movement of the beam hanger in a path in direct vertical

alignment with the polish rod so that the latter will not be subjected to lateral strain. This also applies during the downward movement of the pump end of the walking beam as will be apparent from the showing made in Figure 1.

While I have shown and described the preferred embodiment of my invention, it will be understood that minor changes in construction, combination and arrangement of parts may be made without departing from the spirit and scope of the invention as claimed.

Having thus described the invention, what I claim is:

In a walking beam hanger, an L-shaped member including right angularly disposed portions and one of said portions being in the shape of a shank to extend freely through a bifurcated end of a walking beam and the other portion being of plate-like shape located subjacent to the walking beam, means for pivotally mounting the 20

shank-shaped portion of the member on the walking beam, said plate-like portion of said member having a groove, a bearing member resting in the groove and extending beyond opposite edges of the plate-like portion and having the ends thereof enlarged and tapered to provide sharp bearing edges, straps removably securing the bearing member in the groove and detachably secured to the plate-like portion, bearings 10 engaging the sharp bearing edges of said bearing member, collars removably secured to the ends of the bearing member to prevent accidental displacement of the bearings, means connecting said bearings to a pump rod, an arm pivoted at one end to the L-shaped member adjacent said first means within the bifurcation of the walking beam to engage with the latter during its movement, and a set screw threaded to the free end of the arm and engaging the L-shaped member.

ROY A. DELAY.
